UNITED STATES PATENT OFFICE

2,613,793

CONTROL MECHANISM FOR VENDING AND
LIKE MACHINESFred E. Erickson and Loyal K. Roe, Sacramento,
Calif.; said Roe assignor to said Erickson

Application September 19, 1950, Serial No. 185,552

5 Claims. (Cl. 194—76)

1

This invention relates to vending and like machines and more particularly to the type of operating mechanisms thereof which are rendered capable of actuation upon the insertion thereinto of a designated token piece such as a coin.

An object of the present invention is to provide an amusement machine of the aforementioned character having a sight opening through which one of a series of displays may be viewed in unpredictable sequence upon insertion of a coin into the operating mechanism.

Another object of the invention is to provide mechanism of the class described whose structural character and operational functions have been reduced to the utmost simplicity so as to minimize production, assembly and upkeep costs.

A further object of the invention is to provide a device of the type described in which a selector wheel is utilized, the said wheel having a plurality of defined peripheral increments registerable with a sight opening and arranged to be given unequal rotational impulses so as to position an unpredictable one of the increments in line with the coin actuated sight opening.

Yet another object of the invention is to provide apparatus of the character set forth in which actuation of the internal mechanism may be effected by manual operation of a control lever disposed exteriorly of the apparatus.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to the drawings:

Figure 1 is a front elevational view of the apparatus of the present invention.

Figure 2 is a side elevational cross-sectional view taken along the plane indicated by line 2—2 of Figure 1.

Figure 3 is a top plan cross-sectional view taken along the plane indicated by line 3—3 of Figure 2.

Figure 4 is a side cross-sectional view of the internal construction taken along the plane indicated by line 4—4 of Figure 3.

Figure 5 is a view similar to Figure 2 indicating one position of the parts upon insertion of the token piece, portions of the view being broken away to more clearly illustrate the operation of the device.

Figure 6 is a view similar to Figure 5 indi-

cating another position of the mechanism, portions of the view being broken away as aforesaid.

Figure 7 is a cross-sectional side elevational view of a modified form of our invention.

Figure 8 is a view similar to Figure 5, but with portions of the view being broken away to conserve space on the drawing, illustrating the modified embodiment of the invention.

Figure 9 is a view similar to Figure 6, illustrating the modified mechanism in a different position.

Figure 10 is a diagrammatic wiring diagram of the modified form of the invention.

The mechanism of the present invention is arranged to be operatively inserted in a suitable housing preferably including a front wall 16 and an integrally formed top wall 17, the junction of the walls forming an angularly related wall portion 18. As will be noted from the drawing, the side edges of said walls are constructed with continuous flanges 19 so that the entire unit may be installed in or otherwise secured to a receptacle having an open front and top portion, the particular form of the receptacle not constituting any part of the invention and therefore not illustrated in the drawings.

Mounted for rotation in the housing is a selector wheel 21 having a plurality of defined increments 22 extending radially along the periphery of the wheel. Suitable indicia 23 such as printed words or pictures are placed on each of such increments and are arranged so that the indicia on one of such increments may be viewed through an opening provided in front wall 16. However, a movable shutter 24 is normally disposed between the periphery of wheel 21 and the opening so that the indicia will be hidden from view until a token piece, such as a coin 26, is inserted in the mechanism as will be hereinafter described. Wheel 21 is also provided with a hollow journal 27 fixedly mounted on a side plate 28 which is coextensive with the wheel periphery as will be clear from Figure 4, journal 27 being mounted for rotation on a stationary shaft 29 extending from a bracket 31. Bracket 31 is mounted at right angles to walls 16 and 17 so as to position shaft 29 in parallel relationship therewith; and may be secured to such walls by means of angle clips 32 mounted on the interior surface of the walls and through suitable rivets 33 extending through the inwardly extending flanges of the clips and the bracket. In order to prevent accidental dislodgment of journal 27 and selector wheel 21 from shaft 29, we have provided the distal end of the shaft with an aperture through which a cotter pin 34 or like element may be inserted, washers 36 being inserted on the shaft between

the distal end of the journal and the pin 34 in a manner well known in the art.

Means are provided for imparting unidirectional unequal rotational impulses to the wheel 21 whereby an unpredictable one of the indicia 23 will be aligned with the aforesaid front wall opening, and as here shown, such means include a ratchet wheel 37 fixed to and axially spaced from the wheel side plate 28. Wheel 37 may be secured to the plate by means of rivets 38 with spacer washers 39 inserted therebetween. It will also be noted that ratchet wheel 37 is provided with an axially aligned aperture arranged to fit over a diametrically reduced portion 41 of journal 21, a shoulder 42 of the latter element also serving to maintain the axial spacing of the ratchet wheel from plate 28. To rotate the wheel, we have provided a detent member 43, normally maintained in a radially spaced position relative to the ratchet wheel teeth 44, and which is disposed adjacent the inner wall surface of bracket 31. This member is provided with an inwardly extending extension 46 and it will be clear that upon movement of the member upwardly and to the right (as viewed in Figure 4) extension 46 will engage one of the teeth 44, and upon rapid return of the member to its normal position, the aforesaid rotation will be effected in the direction indicated. To prevent contradirectional rotation, a second detent 47 is utilized, this detent also having an inward extension 48 engageable with ratchet teeth 44. This latter detent may be soldered or otherwise secured to the inner wall surface of bracket 31 as indicated at 49.

As was previously stated, it is desirable to effect the selector wheel rotation from exteriorly of the mechanism housing, and it is therefore necessary to provide an accessible manually operable handle 51 operatively connected to detent member 43. Such interconnection may assume a variety of forms, but we prefer to have handle 51 formed as an integral part of a lever 52 which is pivotally attached to bracket by means of a large headed rivet 53. It will be seen that handle 51 extends outwardly through a slot 55 provided in front wall 16 and is normally maintained in its uppermost or inoperative position by means of a tension spring 54 having one end thereof secured to bracket 31 by means of a rivet 56 and the other end secured to an inwardly extending tab 57 formed at the upper end of lever 52. Detent member 43 is secured to the lower end of the lever by soldering 58 or the like, and it will be seen that as handle 51 is pressed downwardly against the spring tension, the lower end of the lever with its associated detent will be urged toward the right so as to engage the extension 46 with a tooth 44. Upon release of the handle, spring 54 will forcibly snap the lever and detent back into position and thereby cause ratchet wheel and the connected selector wheel to freely rotate on the shaft 27 until the friction will overcome the rotational impulse imparted to the wheel and stop the same. It is desirable that the number of teeth 44 on the ratchet wheel corresponds to the number of increments 22 on the selector wheel so that detent 47 will be in position to prevent counter rotation of the wheel regardless of which of the indicia is aligned with the front plate opening.

As was previously stated, front plate 16 is provided with a sight opening through which the selector wheel indicia may be observed. Such

an opening preferably comprises a generally rectangular cut-out 61, which is completely covered by one or more panes 62 of transparent material such as glass or the like disposed adjacent the inner surface of the front plate. Where two of such panes are used a card 63 or like member is inserted therebetween so as to prevent viewing of the interior of the mechanism except for a small window 64 formed by a cut-out in the card. The window is of substantially the same size as one of the increments 22 on the selector wheel, so that only one of the indicia can be observed in any rotational position of the wheel, it being understood that the periphery of the latter is disposed substantially immediately adjacent the window. Card 63 may have suitable instructions 66 or other information printed on the front side thereof to instruct the user as to the function or operation of the device, and it is, of course, necessary to secure the panes and card in their aforesaid position. Supporting the bottom of the panes is a member 67 including a plate 68 provided with flanges 69 arranged to overlie a substantial portion of the back of the rearmost face and edges of both of the panes. The member is formed integrally with a channel section 71 which may be secured to front plate in a manner to be hereinafter described. The upper ends of the panes are held in position by a downwardly and inwardly bent flange 72 overlying the upper portion of the panes and forming the distal end of a bracket 73 disposed adjacent the walls 16, 17 and 18 and secured to the housing by means of flanges 74 spot welded or the like to flanges 19 of the housing.

Means are provided whereby window 64 is normally covered until the user of the device deposits a coin as aforesaid to uncover the window and enable him to observe the particular indicia 22 aligned with the window. Such means include the previously mentioned shutter 24 which is normally disposed between window 64 and the periphery of the selector wheel. The shutter is mounted on a leg 75 which extends at right angles from an arm 76 which is pivotally mounted on shaft 29 by means of an aperture provided at the distal end of the arm 76. Washers 77 are placed on the shaft between arm 76 and the bracket 31, and a washer 78 is interposed between the other side of the arm and a shoulder 79 formed by a diametrically reduced portion of shaft 29 on which the arm and washers are mounted. To maintain the arm 76, leg 74 and the shutter 24 in its lower or window covering position, a detent 81 is provided which is arranged to bear against the upper surface of an axially elongated stud 82 extending from arm 76 through an aperture 83 formed in bracket 31. In this manner, it will be seen that to raise the shutter it is necessary to lift the stud 82 against the detent pressure so as to cause the shutter to be rotated upwardly along a generally curvate path defined by the radial length of pivot arm 76. Aperture 83 is formed in a manner so as to permit arcuate movement of the stud within the limits necessary to raise and lower the shutter 24.

The token piece, such as coin 26, is arranged to effect the aforesaid lifting of stud 82 in the following manner. It will be noted that a coin slot 86 is provided in wall portion 18, the slot being in communication with a generally vertical coin chute 87 secured by spot welding or the like to the outer surface of bracket 31. When

a coin is placed in the slot 86, it will gravitally descend to the terminus of the chute where its vertical descent will be stopped by a lug 88 disposed below the end of the chute. To prevent the coin from moving outwardly after it leaves the chute, a guide plate 89 is secured at one end thereof to lug 88 and at the other end thereof to a corresponding lug 91 disposed on bracket 31 on the other side of the stud 82. It will be noted that coin 26 in its terminal position, as best seen in Figure 5, is arranged with only the upper portion thereof in horizontal alignment with the stud 82 so that upon movement thereof to the right as indicated in Figure 6, such portion will engage and raise the stud with the attendant raising of the shutter 24. It is desirable to effect such lateral movement of the coin by actuation of the handle 51, and we have therefore provided a U-shaped member 92 arranged to be laterally reciprocated upon movement of lever 52. The member is arranged to slide in a laterally extending groove 93 formed in bracket 31 and is provided with a pair of inwardly protruding lugs 94 arranged to engage the edges of lever 52 so that upon actuation of the latter, member 92 will be moved in its groove, and it will be clear that as handle 51 is moved downwardly, member 92 will move to its right hand position, as in Figure 6, causing coin 26 to raise the stud 82 and lift the shutter. The leading edge 96 of member 92 is preferably rounded to correspond with the peripheral surface of the coin, and stud 82 is provided with an enlarged head 97 under a portion of which the coin is disposed. Upon release of handle 51, lever 52 will be retracted to its normal position due to the action of spring 54, U-member 92 will likewise be retracted to the position shown in Figure 5, coin 26 will fall through the slot defined by lugs 88 and 91, guide plate 89 and bracket 31, and stud 82 will be returned to its downward or shutter closing position. It is understood that as the handle is released, the selector wheel will be again rotated to align a new increment 22 with the window so that on insertion of another coin, the shutter may be opened so as to permit the viewing of a different indicia.

To protect the mechanism from possible damage when the operator is removing the coins from the receptacle in which the device may be placed, as well as to prevent excessive dust accumulation in the moving parts, it is desirable to substantially enclose the same by means such as the removable casing disclosed in the drawing. The casing includes a bottom wall 101, rear wall 102 and side wall 103, the side wall being disposed opposite bracket 31. Rear wall 102 is provided with an angularly related portion 104 which slopes to correspond with the shape of bracket 31, and a flange 106 is formed on the bottom and rear wall whereby the casing may be detachably secured to the bracket as by screws 107.

To prevent unauthorized removal of the device from the receptacle in which it may be placed, a lock mechanism of the familiar type illustrated in the drawing may be utilized. This mechanism includes a casing 111 extending through front plate 16 adjacent the lower edge thereof provided with an internal barrel 112 arranged to rotate upon insertion of the proper key in keyhole 113, rotation of the barrel effecting similar rotation to locking lug 114 which has an end portion 116 arranged to selectively en-

gage and disengage a fixed member in the receptacle.

In Figures 7 through 10, we have disclosed a somewhat modified form of the invention. This embodiment discloses a mechanism similar to that hereinabove set forth except that means are provided to illuminate the selector wheel periphery when the window shutter is opened so that the apparatus may be readily used even though it may be placed in a room with a minimum amount of illumination. Referring to the drawings, it will be seen that a light globe 121 is operatively inserted in the housing, preferably adjacent both the opening 64 and the periphery of selector wheel 21. The globe may be threadedly engaged in a socket member 122 in a manner well known in the art, the latter member being supported on a bracket 123 secured to front plate 16. Means are provided for lighting the globe when the shutter 24 is raised to its window uncovering position illustrated in Figure 7, and it is desirable to effect such illumination by the same mechanism previously described for moving the shutter. In Figure 8, it will be seen that a flexible contact arm 124 is secured to bracket 31 by member 126, the arm having a contact area 127 which is disposed in the path of movement of either stud 82 or its enlarged head 97. A conduit 128 is connected to the member 126 at one end of the former, the other end being connected to a suitable dry cell battery 129 which may be disposed in the receptacle holding the apparatus. The battery, in turn, is connected to socket 122 by a conduit 131 from which it is then grounded as indicated at 132 to the apparatus. It is understood that the stud 82 forms a similar ground 133, so that upon upward movement of stud 82 caused by lateral displacement of the coin, the circuit will be completed and the globe will be lit.

From the foregoing description, it will be seen that an extremely simplified coin operated device has been produced which, while permitting rotation of the selector wheel without insertion of a coin, requires the deposit of a coin to enable the user to observe the indicia appearing on the wheel. It will also be noted that the shutter will open upon movement of the handle from its normal uppermost position to its second position while the selector wheel or rotor will only rotate upon return of the handle to its first position and when the shutter is closed. In this manner, the average user will not fully understand how the various indicia will appear through the window 64 as successive coins are deposited in the device.

We claim:

1. In a coin operated amusement device, a casing including a front plate having an opening therein, a rotor mounted for rotation in said casing and having the periphery thereof divided into substantially equal circumferential segments, indicia appearing on said segments, a ratchet wheel including a plurality of teeth secured to said rotor for rotation therewith, a manually operable handle on said casing, resilient means normally urging said handle in one position, a lever secured to said handle and having a portion thereof engageable with one of said teeth in a second position of said handle, whereby on return of the handle to said first position the lever portion will impart a rotational impulse to said ratchet wheel and said rotor, a shutter member interposed between said rotor periphery and said front plate opening, a slide

member operatively connected with said lever for receiving and moving a coin to raise said shutter from said interposed position upon movement of said handle from its first to second position, means for resiliently returning said shutter member to said interposed position upon return of said handle to its first position.

2. In a coin operated amusement device, a casing including a front plate having an opening therein, a rotor mounted for rotation in said casing and having the periphery thereof divided into substantially equal circumferential segments, indicia appearing on said segments, a ratchet wheel axially aligned with and secured to said rotor, said wheel including a plurality of angularly cut teeth, a manually operable handle mounted on said casing, a lever connected to said handle for movement therewith, a pawl element secured to said lever which on movement of said handle and said lever from a first to second position will slide over said teeth and upon contra movement thereof will engage one of said teeth and impart a rotational impulse to the wheel and rotor, means resiliently urging said handle and lever toward said first position, a substantially opaque shutter member normally disposed between said opening and said rotor periphery, means on said casing for receiving a coin, a coin intercepting element operatively connected to said lever for moving said coin upon movement of the handle from its first to second position, means interconnected to said shutter member in the path of movement of said coin whereby on movement of the latter by said element the shutter member will be moved from its said normal position to place said periphery in sight registration with said opening, and means resiliently urging said shutter member to said normal position.

3. In a coin operated amusement device, a casing including a front plate having an opening therein, a rotor mounted for rotation in said casing and having the periphery thereof divided into substantially equal circumferential segments, indicia appearing on said segments, a ratchet wheel including a plurality of teeth secured to said rotor for rotation therewith, a manually operable handle on said casing, resilient means normally urging said handle in one position, a lever secured to said handle and having a portion thereof engageable with one of said teeth in a second position of said handle, whereby on return of the handle to said first position the lever portion will impart a rotational impulse to said ratchet wheel and said rotor, a shutter member interposed between said rotor periphery and said front plate opening, a slide member operatively connected with said lever for receiving and moving a coin to raise said shutter from said interposed position upon movement of said handle from its first to second position, means for resiliently returning said shutter member to said interposed position upon return of said handle to its first position, a normally open electric circuit including a battery and light globe within said casing, means for closing said circuit upon movement of said handle from its first to second position so as to light the globe when the shutter is in its raised position, and means for breaking said circuit upon return of the shutter to its said interposed position.

4. Coin operated control mechanism comprising a casing having an opening therein, a selector wheel mounted for rotation in said casing and

having the periphery thereof divided into a plurality of substantially equal circumferential segments, the periphery of said wheel being adjacent to said casing opening, a manually operable lever pivotally attached to the casing and having a pawl at one end thereof and resilient means adjacent the other end thereof for normally maintaining said lever in a first position, a ratchet wheel secured to said selector wheel and having teeth thereon engageable by said pawl upon movement of said lever from said first position to a second position and whereby on forcible return of said lever to its first position a unidirectional rotational impulse will be imparted to the wheels, means for preventing counterrotation of said wheels, a shutter member operatively mounted between said opening and wheel periphery, an arm operatively connected to said shutter, means in said casing for receiving a coin, means operable on movement of said lever from its first to second position for urging said coin against said arm and moving the shutter so as to place said opening and wheel segments in sight registration, and means resiliently urging said shutter toward its interposed position.

5. Coin operated control mechanism comprising a casing having an opening therein, a selector wheel mounted for rotation in said casing and having the periphery thereof divided into a plurality of substantially equal circumferential segments, the periphery of said wheel being adjacent to said casing opening, a manually operable lever pivotally attached to the casing and having a pawl at one end thereof and resilient means adjacent the other end thereof for normally maintaining said lever in a first position, a ratchet wheel secured to said selector wheel and having teeth thereon engageable by said pawl upon movement of said lever from said first position to a second position and whereby on forcible return of said lever to its first position a unidirectional impulse will be imparted to the wheels, means for preventing counter-rotation of said wheels, a shutter member operatively mounted between said opening and wheel periphery, an arm operatively connected to said shutter, coin receiving and guiding means in said casing, a slide member operatively connected to said lever and arranged for lineal movement upon pivotal movement of the lever, said slide member having a coin engaging face thereon for conveying a coin from said receiving means toward said shutter arm for moving the latter and the shutter so as to place said opening and wheel segments in sight registration, and means resiliently urging said shutter to its normal position between the opening and wheel periphery.
